UNITED STATES PATENT OFFICE.

HENRY C. DORNHECKER, OF BALTIMORE, MARYLAND.

FLOOR WAXER AND POLISHER.

Application filed March 30, 1927. Serial No. 179,490.

The invention relates to devices for waxing and polishing floors.

The principal object of the invention, generally stated, is to provide a manually operable device adapted to be simply pushed back and forth over a floor and convertible for use in applying wax and subsequent employment for effecting rubbing thereof to impart the desired smooth surface and high luster to the floor.

An important object of the invention is to provide a device of this character in which the polishing or rubbing means is detachable from the remainder of the device so that the wax applying function may be carried out, the device possessing the advantage of combining two different tools in one.

Another object of the invention is to provide a floor treating device of this character provided with novel means for maintaining the rubbing or polishing member in operative relation to the main or wax applying portion of the device, the parts cooperating and certain of them interfitting whereby dis- placement of the rubbing member while in use will be avoided.

Another important object of the invention is to provide a floor treating device of the reservoir type and of such construction that a relatively large mass of wax may be contained therein and applied in predetermined quantities to the floor or other surface by an endless belt movable step by step in accordance with the direction of movement of the device, means being provided for preventing the passage of an excess quantity of wax onto the floor or other surface.

A more specific object of the invention is the provision of a device of this nature having gravity operated means frictionally engaging the belt and acting as a scraper to prevent more than the proper quantity of wax from being applied to the surface treated.

Still another object is to provide a waxer and polisher having means mounted on the upper stretch of the belt for positively preventing the wax from passing beyond or over the edges thereof and getting onto the inner face of the belt with resultant gumming of the belt carrying rollers.

Yet another object is to provide an apparatus of this type having means cooperating with the upper stretch of the belt and one of the rollers carrying the same for the pur-

pose of exerting a ratchet-like action which will permit the belt to move and apply wax to the floor when the device is moved in one direction only, the reverse movement being idle except for the smoothing action on the previously applied wax.

An additional object is the provision of a device or tool of this character which will be simple and inexpensive to manufacture, easy to use, rapid and efficient in action, durable in service, and a general improvement in the art.

With the above and other objects and advantages in view, the invention preferably consists in the combination and arrangement of parts as well as the detailed construction thereof to be hereinafter more fully described and claimed, and illustrated in the accompanying drawings in which:

Figure 1 is a side elevation of the complete device with the polishing member applied thereto,

Figure 2 is a top plan view,

Figure 3 is a plan view of the top of the polishing or rubbing member removed,

Figure 4 is a vertical longitudinal section taken on substantially the line 4—4 of Figure 5,

Figure 5 is a horizontal section taken on substantially the line 5—5 of Figure 4,

Figure 6 is a vertical cross section taken on the line 6—6 of Figure 4 with the roller in elevation, and

Figure 7 is a vertical cross section on the line 7—7 of Figure 4 with the polishing member removed.

Referring more particularly to the drawings, I have shown the device as comprising a preferably elongated rectangular hollow body 1 open at its bottom and having its top closed by a wall 2 provided with an opening 3 normally closed by a hinged door 4 mounted in some convenient manner. In the present instance the mounting is shown as consisting of arms 5 cast upon the door and pivoted by rivets or the like 6 to apertured lugs 7 rising from the top wall 2. The door is also preferably provided with a finger piece 8 by means of which it may be handled and swung to open or closed position. Inasmuch as the device is intended to be alternately pushed and pulled over the floor or other surface to be treated, its top is preferably provided with spaced ears 9 between which is pivoted, at 10, a socket member 11 within which is

secured a suitable handle 12 of any desired or convenient length.

Extending transversely of the body and projecting slightly beyond the open bottom thereof are rollers 13 which are journally mounted and which are here disclosed as rotatable upon stationary spindles or bolts 14 which pass through the body as particularly illustrated in Figures 5 and 6. Trained about these rollers is an endless belt 15 of canvas or other suitable flexible material and which serves as the means for conveying wax and applying it to the floor or other surface to be treated. The space within the top of the casing and above the belt is intended for the storage of wax which is introduced through the opening 3 when the cover or door 4 is in open position and it is clear that when the device is drawn along the floor or other surface with the lower stretch of the belt contacting the same the movement of the belt will cause the wax to be applied to the floor in a manner to be hereinafter more fully explained.

To support and guide the upper stretch of the belt and prevent undue sagging thereof under the weight of the mass of wax within the casing, I preferably provide ledges or flanges 16 which may be formed integrally upon the sides of the casing, for instance by casting, and which project toward each other. These ledges serve as supporting means for a slidably mounted wedge 17 which is disposed thereon and which has its thinner end adapted to engage and jam between the upper stretch of the belt and one of the rollers 13 for locking the parts and preventing movement of the belt or rotation of the rollers when the device is moved along the floor in one direction. To limit movement of the wedge member 17 away from the adjacent roller, I provide some suitable stops which may, in actual practice, be simply webs 18 beneath the ledges and formed on the sides of the casing, these webs being located in the path of movement of a cross-head like member 19 here represented as secured to the underside of the wedge though equally capable of being formed integrally therewith if found advisable for any reason.

To prevent excess wax from being carried out of the device by the belt and applied to the floor, I preferably provide a gravity actuated scraper member 20 mounted for vertical sliding movement within one end of the casing. Actually, this element may consist of a block of rather heavy material, preferably metal and to increase its frictional effect upon the belt it may be encased within a fabric or other flexible envelope 21. To avoid displacement of this member longitudinally of the casing, I preferably employ an angular stop and guide 22 mounted beneath the top wall 2 as for instance by means of a screw 23, this member also serving as a stop for limiting

downward swinging movement of the door or cover 4. Clearly, any equivalent guide means for the block 20 might be provided, but this is a highly convenient arrangement.

During the course of experimentation and later in actual practice, I have found that there is quite frequently a tendency of the wax to slip, drop or otherwise pass over the side edges of the upper stretch of the belt. If and when this occurs it is clear that wax will fall upon the top surface of the lower stretch and will be transferred therefrom to the rollers with the result that the rollers become gummed up. To avoid such a contingency, I have found it expedient to employ retaining means at the edges of the belt in overlapping relation thereto. Actually, such means may consist simply of a U-shaped frame-like member 24 formed conveniently from a suitable length of rod of substantial gauge bent into the desired shape. This frame-like member is of such size as to fit comparatively snugly within the casing with its right portion disposed adjacent the scraper member 20 and with its arms projecting over and beyond the wedge member 17. Gravity is relied upon to hold this member in proper contact with the belt and it is of course clear that the arms of this member will act to prevent the wax from passing beyond the side edges of the belt.

It is well known that wax commonly used for polishing floors is in the form of a plastic mass and is generally put up in tin cans from which a handful is taken out as needed. When this material is used in my device one or more handfuls is simply placed upon the upper stretch of the belt. The mass has a certain amount of cohesion but as the vehicle or oily matter dries out, as it will in a comparatively short time, there is a tendency for the material to break up and crumble into pieces of widely different sizes. It is on account of this crumbling tendency that the U-shaped member is provided, the side arms 24 keeping this crumbled material from passing over the edges of the belt. Regardless of how small the pieces of wax may become, they will not pass over the roller 13 with which the wedge cooperates for the reason that the belt never moves in this direction but always in the opposite direction tending to drag the wax under the member 20.

The polishing member preferably comprises a brush indicated as a whole by the numeral 25, this brush including a back 26 carrying groups of bristle tufts 27. The back is preferably of the same length and width as the casing and is adapted to fit against the open bottom thereof, the top surface of the back being formed with partially cylindrical recesses 28 receiving the projecting portions of the rollers and the portion of the belt immediately engaging the rollers. The engagement of the rollers and belt within the

recesses will of course act to prevent shifting of the polishing member either laterally or longitudinally with respect to the casing. It of course becomes necessary to hold this 5 polishing member to the casing, and an effective means for accomplishing this preferably comprises straps or other flexible members 29 suitably secured to the ends of the back 26 and carrying female snap fastener elements 30 adapted to be engaged upon coacting male elements 31 secured upon the ends of the casing in any suitable manner as for instance by having their shanks 32 embedded therein during casting.

10 In order to avoid damaging baseboards and the legs or other parts of furniture during the use of the device it is preferable to provide a continuous felt or other similar yieldable buffer strip 33 on the casing at its 15 open end, and a similar strip 34 on the edges of the back 26 of the polishing member.

In the operation of the device, it is of course apparent that when it is intended to use it for applying wax to a floor or other surface, 20 the polishing member must be detached, this being readily accomplished simply by disengaging the fastener elements 30 from the fastener elements 31 so that the polishing member may simply drop away or the remainder of the device lifted off from it. Wax is placed within the casing through the opening in the top thereof. The operator then sets the device upon the floor and it is of course obvious that it will rest upon the lower 25 stretch of the belt and the rollers. When the device is pushed along in one direction it is clear that the rollers 13 will be rotated and the belt 15 moved. During the movement of the belt, it drags a certain amount of the wax supported upon it beneath the scraper member 20 and naturally applies this wax to the floor, the scraper member 20 acting to smooth off the wax adhering to the belt and thus preventing an excess quantity from being 30 applied to the floor. When the device is moved in the other direction, the drag of the upper stretch of the belt upon the wedge member 17 will cause the latter to move toward the adjacent roller and jam between it and the belt, thus preventing movement of the belt. When the device is again moved in the first 35 direction the wedge member shifts out of engagement with the roller and the belt moves another step, the degree of movement of course depending upon the length of the stroke given to the entire device. There is consequently obtained a species of ratchet-like action which will result in application of wax upon one stroke and idle dragging of the device over the previous waxed spot on the reverse stroke. This reverse or idle stroke causes the wax to be smoothed out and evenly distributed over the surface.

After the wax has been thus applied, and 40 it is desired to polish the surface, the op-

erator applies the polishing member by engaging the back member 26 thereof against the belt and rollers and by snapping the fasteners 30 onto the fasteners 31. The waxing mechanism thereupon becomes inactive as 70 there is nothing to move the belt or rollers, and the device is operated in the same manner as any other polisher by simply sliding it back and forth over the surface to be polished.

From the foregoing description and a study 75 of the drawings it will be apparent that I have thus provided a simply constructed, inexpensive and very easily operated device for the purpose specified and one which will be of particular advantage in making it unnecessary for the operator to get down upon his hands and knees for the purpose of applying the wax as is generally the custom. The device not only saves labor and annoyance in this respect but applies the wax more smoothly and uniformly than is easily possible by hand application. It is really believed that the construction, operation and advantages 80 will be readily apparent to one skilled in the art without further explanation. 90

While I have shown and described a preferred embodiment of the invention, it should be understood that the disclosure is merely an exemplification of the principles involved as the right is reserved to make all such changes 95 in the details of construction as will widen the field of utility and increase the adaptability of the device provided such changes constitute no departure from the spirit of the invention or the scope of the claims hereunto appended. 100

Having thus described the invention, I claim:

1. In a floor waxer and polisher, a casing, waxing means within the casing embodying rollers and a belt, the lower stretch of the belt 105 and portions of the rollers projecting beyond the bottom of the casing, and a polishing member including a brush disposable against the open bottom of the casing, and means carried by said polishing member and detachably engageable with the casing, said polishing member being formed as a brush having a back formed with recesses receiving the projecting portions of the rollers and the portions of the belt engaged thereagainst, said engagement acting to prevent lateral and longitudinal displacement of the polishing member with respect to the casing. 110

2. In a floor waxer and polisher, a casing, waxing means within the casing embodying rollers and a belt, the lower stretch of the belt and portions of the rollers projecting beyond the bottom of the casing, and a polishing member including a brush disposable against the open bottom of the casing, and means carried by said polishing member and detachably engageable with the casing, said polishing member being formed as a brush having a back formed with recesses receiving the projecting portions of the rollers and the 125 130

portions of the belt engaged thereagainst, said engagement acting to prevent lateral and longitudinal displacement of the polishing member with respect to the casing, the securing means for the polishing member including flexible elements thereon carrying separable fastener elements and other separable fastener elements on the casing cooperating with the first mentioned separable fastener elements.

3. In a floor waxer and polisher, a casing, waxing means within the casing embodying rollers and a belt, the lower stretch of the belt and portions of the rollers projecting beyond the bottom of the casing, and a polishing member including a brush disposable against the open bottom of the casing, and means carried by said polishing member and detachably engageable with the casing, said polishing member being formed as a brush having a back formed with recesses receiving the projecting portions of the rollers and the portions of the belt engaged thereagainst, said engagement acting to prevent lateral and longitudinal displacement of the polishing member with respect to the casing, said polishing member having its side edges and ends flush with the sides and ends of the casing, the edges of the polishing member and the outside of the casing near the open bottom thereof being provided with continuous buffer members of yieldable material extending thereabout.

4. In a floor waxing device, a casing, rollers journaled within said casing, a continuous belt trained about the rollers and having its lower stretch projecting beyond the bottom of the casing, the space within the casing above the belt serving as a storage compartment for wax, and a gravity operated scraper member mounted for vertical movement within one end portion of the casing and resting upon the belt at one roller.

5. In a floor waxing device, a casing, rollers journaled within said casing, a continuous belt trained about the rollers and having its lower stretch projecting beyond the bottom of the casing, the space within the casing above the belt serving as a storage compartment for wax, a gravity operated scraper member mounted for vertical movement within one end portion of the casing and resting upon the belt at one roller, and guide means for said scraper member for preventing displacement thereof longitudinally of the casing and confining it to vertical movement.

6. In a device of the character described, a casing having an open bottom, rollers journaled transversely of the casing, an endless belt trained about the rollers and projecting beyond the open bottom of the casing, and means carried by the upper stretch of the belt at the edges thereof to prevent wax placed on the belt from passing beyond said edges.

7. In a device of the character described, a casing having an open bottom, rollers journaled transversely in the casing, an endless belt trained about the rollers and having its lower stretch projecting beyond said open bottom, the upper stretch of the belt being adapted to support a mass of wax, a gravity operated scraper member resting upon the upper stretch of the belt at one roller for preventing excess discharge of wax, and a guide lug within the casing engaging said scraper.

8. In a device of the character described, a casing having an open bottom, rollers journaled transversely in the casing, an endless belt trained about the rollers and having its lower stretch projecting beyond said open bottom, the upper stretch of the belt being adapted to support a mass of wax, and a gravity operated scraper member resting upon the upper stretch of the belt at one roller for preventing excess discharge of wax, said scraper member being formed as a weight enclosed within a flexible envelope.

9. In a device of the character described, a casing having an open bottom, rollers journaled transversely in the casing, an endless belt trained about the rollers and having its lower stretch projecting beyond said open bottom, the upper stretch of the belt being adapted to support a mass of wax, a gravity operated block-like scraper member resting upon the upper stretch of the belt at one roller for preventing excess discharge of wax, and a guide member depending from the top of the casing and engaging said scraper member to prevent displacement thereof longitudinally of the casing.

10. In a device of the character described, a casing having an open bottom, rollers journaled transversely in the casing, an endless belt trained about the rollers and having its lower stretch projecting beyond said open bottom, the upper stretch of the belt being adapted to support a mass of wax, a gravity operated scraper member resting upon the upper stretch of the belt at one roller for preventing excess discharge of wax, a guide member depending from the top of the casing and engaging said scraper member to prevent displacement thereof longitudinally of the casing, the top of the casing having a hinged door, and said guide projecting beyond the door opening to serve as a stop limiting inward movement of the door.

11. In a device of the character described, a casing having an open bottom, rollers journaled transversely in the casing, an endless belt trained about the rollers and having its lower stretch projecting beyond said open bottom, the upper stretch of the belt being adapted to support a mass of wax, a gravity operated scraper member resting upon the upper stretch of the belt at one roller for preventing excess discharge of wax, and a member mounted upon and gravitationally en-

gaging the upper stretch of the belt at the edges thereof to prevent the wax from passing over said edges.

12. In a device of the character described, 5 a casing having an open bottom, rollers journaled transversely in the casing, an endless belt trained about the rollers and having its lower stretch projecting beyond said open bottom, the upper stretch of the belt being 10 adapted to support a mass of wax, a gravity operated scraper member resting upon the upper stretch of the belt at one roller for preventing excess discharge of wax, and a retaining member carried upon and slidably engaging 15 the upper stretch of the belt and including portions located at the edges of the belt for preventing wax from passing thereover.

13. In a device of the character described, 20 a casing having an open bottom, rollers journaled transversely in the casing, an endless belt trained about the rollers and having its lower stretch projecting beyond said open bottom, the upper stretch of the belt being 25 adapted to support a mass of wax, a gravity operated scraper member resting upon the upper stretch of the belt at one roller for preventing excess discharge of wax, and a U-shaped retaining member resting upon the upper stretch of the belt with its bight portion 30 disposed against said scraper member and its arms lying adjacent the sides of the casing to cover the edges of the belt.

14. In a device of the character described, 35 a casing having an open bottom, transverse rollers journaled in the casing, an endless belt trained about said rollers and having its lower stretch projecting beyond the open bottom of the casing, longitudinally extending 40 guide ledges beneath the upper stretch of the belt, and means movably mounted upon said guide ledges and cooperating with the upper stretch of the belt and one roller for preventing rotation of the rollers and movement 45 of the belt when the device is moved in one direction.

15. In a device of the character described, 50 a casing having an open bottom, transverse rollers journaled in the casing, an endless belt trained about said rollers and having its lower stretch projecting beyond the open bottom of the casing, longitudinally extending 55 guide ledges beneath the upper stretch of the belt, and means movably mounted upon said guide ledges and cooperating with the upper stretch of the belt and one roller for preventing rotation of the rollers and movement of the belt when the device is moved in one direction, said means comprising a wedge having its tapered end disposed toward the adjacent roller.

16. In a device of the character described, 60 a casing having an open bottom, transverse rollers journaled in the casing, an endless belt trained about said rollers and having its

lower stretch projecting beyond the open bottom of the casing, longitudinally extending 65 guide ledges beneath the upper stretch of the belt, means movably mounted upon said guide ledges and cooperating with the upper stretch of the belt and one roller for preventing rotation of the rollers and movement of the belt when the device is moved in one direction, and stop means on said ledges for limiting 70 movement of said means in a direction away from the adjacent roller.

17. In a device of the character described, 75 a casing having an open bottom, transverse rollers journaled in the casing, an endless belt trained about said rollers and having its lower stretch projecting beyond the open 80 bottom of the casing, longitudinally extending guide ledges beneath the upper stretch of the belt, and means movably mounted along said guide ledges and cooperating with the upper stretch of the belt and one roller 85 for preventing rotation of the rollers and movement of the belt when the device is moved in one direction, said means comprising a wedge having its tapered end disposed toward the adjacent roller, said wedge 90 having its major portion located above and upon the ledges and having a combined guide and retaining portion located beneath the ledges.

18. In a device of the character described, 95 a casing, rollers journaled within the casing, an endless belt trained about the rollers and having its lower stretch projecting beyond the bottom of the casing, a portion of the space above the upper stretch of the belt serving as a compartment for the reception of floor wax, and means resting upon the upper stretch of the belt and overlying the edges thereof for preventing the wax from passing over and beyond said edges.

19. In a device of the character described, 100 a casing, rollers journaled within the casing, an endless belt trained about the rollers and having its lower stretch projecting beyond the bottom of the casing, a portion of the space above the upper stretch of the belt serving as a compartment for the reception of floor wax, and means resting upon the upper stretch of the belt and overlying the edges thereof for preventing the wax from passing over and beyond said edges, said means further including a portion extending transversely of the belt.

20. In a device of the character described, 110 a casing having an open bottom, rollers journaled in the casing, a belt trained about the rollers and having its lower stretch projecting beyond said open bottom, guide means within the casing beneath the edges of the upper stretch of the belt, a portion of the space above the upper stretch of the belt serving as a storage compartment for floor wax, and a member lying upon and supported by the up- 115 120 125

per stretch and engaging upon the side edges thereof for preventing the wax from passing beyond said edges.

21. In a device of the character described, 5 a casing having an open bottom, rollers journaled in the casing, a belt trained about the rollers and having its lower stretch projecting beyond said bottom, guide means within the casing beneath the edges of the upper stretch of the belt, a portion of the space

above the upper stretch of the belt serving as a storage compartment for floor wax, and a member lying upon and supported by the upper stretch and engaging upon the side edges thereof for preventing the wax from 15 passing beyond said edges, said member being of U-shape and having its bight portion extending transversely of the belt.

In testimony whereof I affix my signature.

HENRY C. DORNHECKER.
